UNITED STATES PATENT OFFICE.

JAMES R. JACKSON, OF NASHVILLE, TENNESSEE.

AUTOMATIC GATE PROPELLER.

Application filed March 17, 1921. Serial No. 453,023.

This invention aims to provide novel means whereby a gate may be operated by the wheels of an approaching vehicle, the construction being such that the gate may 5 be operated by hand, if desired.

Another object of the invention is to improve the construction of the accelerator whereby motion is transmitted to the gate.

In the drawings:—

Figure 1 shows in top plan, a gate and attendant parts, constructed in accordance with the invention;

Figure 2 is a vertical section taken approximately on the line 2—2 of Fig. 1, the view being, in substance, an elevation showing certain of the posts and parts carried thereby;

Figure 3 is an elevation wherein the gate is shown closed, certain of the posts, which 20 are adjacent to the observer, having been omitted in this figure of the drawings;

Figure 4 is a fragmental elevation showing a portion of the gate and the post whereon the gate is supported, the accelerator appearing for the most part in section, as does the casing wherein the accelerator is enclosed.

Figure 5 is a sectional detail, showing the means whereby, at the will of an operator, 30 certain of the flexible elements may be adjusted, tightened or loosened, parts appearing in elevation;

Figure 6 is a sectional detail showing the mounting of the drum.

Figure 7 is a transverse section of the drum.

Referring to Figures 1, 2 and 3, the numeral 1 designates a support or main post which is supplied with bearings 2, and with 40 a lower hanger 3. A tubular shaft 4 is journaled in the bearings 2. The shaft 4 is passed through the loop of the top hinge 60 of a gate 5 and is held rigidly at 61 in the loop. The top bearing 2 and the hanger 3 support the gate 5.

A vertically swinging latch 6 is mounted on the gate 5 and is adapted to cooperate with a keeper 7 on a striking post 8. Additional gate-engaging latch mechanism 56 of any desired sort may be mounted on the post 8. Stop posts 28 are located on opposite sides of the main post 1 and carry keepers 27. Posts 38 are located outwardly of the posts 28.

A casing 9 is secured to the upper end of the post 1. A first shaft 10 is journaled in

the casing 9 and in the upper end of the tubular shaft 4 (Fig. 4) which carries the gate 5. A second shaft 11 is journaled in the casing 9.

An upper pinion 12 and a lower gear wheel 14 are secured to the shaft 11. A gear wheel 15 is secured to the shaft 10. A pinion 16 is secured to the shaft 4 adjacent to its end. The gear wheel 15 meshes with the pinion 12, and the pinion 16 meshes with the gear wheel 14. The pinions 12 and 16, and the gear wheels 15 and 14, constitute a speed-increasing gear train, or accelerator, whereby motion is transmitted from the 70 shaft 10 to the shaft 4 and, consequently, to the gate 5. A drum 17 is mounted on the upper end of the shaft 10. The drum 17 has a recess 18, defining shoulders 19. The shaft 10 carries a projection 20 located in 75 the recess 18 and adapted to cooperate with the shoulders 19. The construction is such that the drum 17 may have a slight movement independently of the shaft 10, a lost motion connection between the drum 17 and the shaft 10 thus being provided. The utility of this construction will be made manifest hereinafter. A plate 729 is secured at 732 to the bottom of the drum 17 and surrounds the shaft 10 closely, the plate, in 80 conjunction with the projection 20, constituting means for holding the drum on the shaft.

Housings 21 are mounted on the ground, adjacent to the post 38 and have outstanding bearings 22. A bearing 23 is mounted in the ground in spaced relation to the outer end of each housing 21. First shafts 24 are mounted to rock in the housings 21 and in the bearings 23. The shafts 24 have cranks 25, 95 located between the housings 21 and the bearings 23. At their inner ends, the shafts 24 are provided with crank arms 26. Second shafts 29 are mounted to rock in the bearings 22 and have cranks 30 disposed between the bearings 22. The inner ends of the shafts 29 are equipped with crank arms 31.

Each post 38 carries a projecting cap plate 32 supporting idlers 33. The posts 38 are provided adjacent to their lower ends with frames 54 wherein idlers 34 are journaled. Flexible elements 35 and 36 are wound in opposite directions around the drum 17 and are secured at their inner ends 110 thereto. The flexible elements 36 extend outwardly and oppositely over the most for-

ward of the idlers 33 and terminate in handles 37. The handles 37 are of sufficient weight to be useful in taking the slack out of the flexible elements 36.

5 Lines 39 and 40 are branched off from the flexible elements 35. The lines 39 and 40 extend outwardly and oppositely over certain of the idlers 33, and thence downwardly, traversing the idlers 34, and extending in opposite directions therefrom.

10 The flexible elements 40 are secured to the crank arms 31 of the shafts 29 while the flexible elements 39 are secured to the crank arms 26 of the shafts 24. A means is provided whereby the elements 39 and 40 may be connected adjustably to the parts where-with they coact. Thus, taking the crank arm 26 as typical, it will be observed that the crank arm 26 terminates in a finger 41, whereon a spool 42 is journaled for adjustment, the spool being held in place by a set screw 43. The spool 42 is provided with a perforated ear 730 to which the end of the flexible element is secured. The flexible element 40 is wound about the spool 42 of the arm 31 and is engaged with the ear thereof, as aforesaid. By rotating the spools 42, the flexible elements will be reeled thereon, and when the set screws 43 are tightened 30 up, the position of the crank arm 26 and of the crank arm 31 will be adjusted. Handles 44, in the form of weights, are interposed in the flexible elements 40 and 39.

15 An arm 45 projects from the drum 17. 35 A flexible element 46 is attached to the arm 45 and is carried between guide rollers 47 journaled in a bracket 48 mounted on the gate 5. The flexible element 46 is connected at 49 to the latch 6. The drum 17 includes 40 a top 731 which, resting on the end of the shaft 10 supports the drum.

20 Suppose that a vehicle is approaching the device from the left, looking from the hinge post toward the latch post in Figures 1 and 45 2. The vehicle drives clear of the outside left hand crank 30, and engages the inside left hand crank 25, which is inclined with respect to the horizontal. The crank 25 transmits motion to the corresponding shaft 24. The crank arm 26 on the inside left hand shaft 24 operates the drum 17 by way 50 of the flexible elements 35-40.

25 The drum 17 rotates independently of the shaft 10, owing to the provision of the lost motion connection 20-19. When the drum 17 rotates independently of the shaft 10, the flexible element 46 is pulled, and the latch 6 is raised out of engagement with the keeper 7, the gate 5 thus being set free for 55 swinging movement. One of the shoulders 19 now engages the projection 20, and motion is transmitted from the drum 17 to the shaft 10, the shaft 10 being rotated. 60 From the shaft 10, rotation is imparted to 65 the shaft 11 by way of the gear wheel 15

and the pinion 12. From the shaft 11, rotation is imparted to the shaft 4, by way of the gear wheel 14 and the pinion 16. When the shaft 4 is rotated, the gate 5 is swung to an open position, rapidly, owing to the ratio 70 established by the relative diameters of the parts 15-12-14-16, the ratio being inversely as between the two shafts, as two to one, the shaft 4 rotating twice as fast as the shaft 10. As the gate swings open, the 75 latch 6 engages with the keeper 27 on the right hand post 28.

When the drum 17 is rotated, as aforesaid, clockwise, the right hand flexible element 35 in Figure 1 is reeled on the drum, and the right hand flexible element 39 in Figure 2 is raised, thereby elevating the corresponding closing crank 25 to an angle of substantially forty-five degrees, being the outside right hand crank. The vehicle drives clear 85 of the inside right hand crank 30 in Figure 1 and engages the corresponding closing crank 25, being the outer right hand crank, whereupon the crank 25 is swung downward to a horizontal position, the corresponding shaft 24 being rotated, and motion being transmitted through the drum 17, by way of the right hand flexible elements 39 and 35. Owing to the lost motion connection between 90 the drum 17 and the shaft 10, the first operation is to disengage the latch 6 from the keeper 27 on the post 28. Then, the gate is swung to a closed position with respect to the striking post 8.

95 The foregoing operation presupposes that the vehicle is moving in Figures 1 and 2 from left to right. If the vehicle moves in an opposite direction, then the cranks 30 become the actuating elements, the inside right hand crank 30 standing at substantially forty-five degrees, being the opening crank, the flexible elements 40 and the crank arms 31 transmitting motion to the drum 17, through the flexible elements 35.

100 Having thus described the invention, what is claimed is:—

1. In an apparatus of the class described, a rotatably mounted shaft, a gate; means for connecting the gate with the shaft, another shaft supported for rocking movement and having a vehicle engaging crank and an arm, a spool adjustably journaled on said arm and a flexible element connected operatively with the shaft and wound about 105 the spool and secured thereto.

2. In a device of the class described, a pair of shafts mounted in longitudinal alignment for independent rotation, a gate mounted on one shaft, means for operating 110 the other shaft, and a speed increasing gear train connecting the shafts.

115 In testimony that I claim the foregoing as my own, I have hereto affixed my signature.

JAMES R. JACKSON.
